MACHINE FOR BOOKING MATCHES

John R. Nolan, Larchmont, N. Y., assignor to The
Diamond Match Company, New York, N. Y., a
corporation of Delaware

Application May 17, 1940, Serial No. 335,661

4 Claims. (Cl. 93—2)

This invention relates to machines for booking matches, and more particularly to a machine of the type disclosed in Letters Patent of the United States No. 1,042,472, dated October 29, 1912, to which reference may be had.

The present invention concerns mechanism of simple and inexpensive construction for efficiently ejecting from the pockets of the travelling cover-and-match card carrier of a booking machine, match cards from which the covers have been omitted, and this without disturbing the properly assembled covers and cards borne by the carrier. A form of mechanism for this purpose is the subject of an application filed by Michael Paridon, February 21, 1940, under Serial No. 320,002, which mechanism, generally described, comprises a crank-actuated match ejecting dog movable transversely and vertically in respect to the path of the carrier, and means including a cam-controlled rocker-frame for supporting and guiding the dog in its travel, the relative angularity of the frame to the plane of the carrier being determined by the presence or absence of a cover in the carrier; that is to say, in the presence of a cover effective to limit the descent of the rocker frame the latter is positioned to guide the dog with its tooth or acting member above and out of contact with the cover, whereas in the absence of a cover the frame is permitted to descend sufficiently to guide the dog with its tooth in abutting relation to the adjacent ends of the uncovered match card or cards borne by the carrier.

In accordance with my invention, the crank connection for the match ejecting dog, the rocker frame, and the cam actuating means for the frame, are eliminated. Instead a simple pendulous element of novel construction, which is pivotally supported by a reciprocating head, is so formed and arranged that in the presence of a cover in a pocket of the carrier the element in the major portions of its forward and backward strokes is guided and supported by the carrier in a plane above the adjacent cover, whereas in the absence of a cover the element in its forward stroke rides upon the upper surface of the carrier and above the underlying match card until the element reaches the limit of its stroke, whereupon the element automatically assumes a substantially vertical position with its acting portion in alignment with the pocket of the carrier, which portion in the succeeding back stroke of the dog enters and traverses the pocket of the carrier in a manner to abut the opposing ends of the match card or cards, thus positively ejecting such card or cards from the carrier.

The invention also comprises novel features of construction and combinations of parts which in a preferred form will be hereinafter described, the scope of the invention being expressed in the appended claims.

In the drawings—

Figure 1 is a front elevation of a portion of a match booking machine equipped with match card removing mechanism embodying the principle of my invention.

Fig. 2 is a partial transverse vertical section, as on the line 2—2 of Fig. 1, showing the said mechanism in elevation and at the end of its rearward stroke, and also in dotted lines at the end of its forward stroke, the frame of the booking machine being indicated in dotted lines.

Fig. 3 is a plan of the said mechanism and a pair of adjacent carrier links, one of the links being shown with a cover therein and the other link with a match card devoid of a cover, and the match ejecting elements for the respective links being represented in their relative positions at the limit of their forward stroke.

Fig. 4 is a transverse vertical section, as on the line 4—4 of Fig. 3.

Fig. 5 is an elevation of the forward or right hand portion of the mechanism shown in Fig. 4.

Figs. 6 and 7 are transverse sections through the carrier and its guide trough, showing an ejecting element in succeeding positions in relation to a carrier link containing a match card and cover.

Figs. 8, 9 and 10 are similar sections, showing the ejecting element in succeeding positions in relation to a carrier link containing match cards devoid of a cover.

Fig. 11 is a perspective view of a portion of a reciprocating structure for supporting a pair of match ejecting elements.

Fig. 12 is a similar view of one of the said elements.

Referring to the drawings, 15 designates the supporting frame including the table 16 of a typical match booking machine, and 17 a portion of a carrier which is intermittently actuated by 45 and from the main cam shaft of the machine through suitable gearing. The form of carrier illustrated comprises an endless chain of pocketed links adapted to travel in a longitudinally extending guide trough 18 suitably located at the rear of the table, each link of the chain including a base 19 with parallel side walls 20 having inwardly overhanging flanges 21, and including a spring clamping leaf 22 which is secured at one end to the base and inclined upwardly and rearwardly so 55

that its free upper end coacts with the under surfaces of the flanges.

In each dwell of the carrier in one location of its path two covers C, each folded at one end, are inserted in adjacent carrier links, with the folded ends f projecting rearwardly beyond the links while the bodies of the covers are yieldingly clamped against the flanges 21 by the spring leaves 22. In the continued travel of the carrier 10 the end folded covers borne thereby are positioned in another location where match cards M are inserted flatwise in the carrier links which were previously presented to the cover inserting station, the cards being pushed between the spring 15 leaves and the under surfaces of the covers contained in each link so that the uncut bases of the cards are inclosed by the folded ends of the covers. Usually two counterpart cards of matches, one card superposed on the other, are inserted in each 20 link. In the continued progress of the carrier the contents of the links are transported to stitching mechanism S; thence (if not "pre-frictioned") to friction-paint applying mechanism P; thence to succeeding stations in the book making cycle, as 25 usual.

Mechanism embodying my invention for removing match cards from carrier links from which covers have been omitted at the cover-supply station, is mounted adjacent the path of the carrier in a location following the card-inserting station, preferably between the stitchers and the friction-paint applying agency, which mechanism in the exemplifying form is as follows:

35 Fixed to the rear wall of the trough 18 is a bracket 23 having lateral guides 24 in and between which is a slide 25 that is reciprocated in timed relation to the carrier; that is to say, during each dwell of the carrier the slide moves to 40 and from the adjacent side of the carrier, the stroke of the head somewhat exceeding the width of the trough. Any suitable means for actuating the slide may be employed. In the present instance the slide is pivotally connected by means 45 of a link 26 with the upstanding arm 27 of a bell-crank fulcrumed on a stud-shaft 28 extending from the frame 29 of the stitcher. The other arm 30 of the bell-crank has a lateral roll 50 31 operatively fitted in the race of a face cam 32 fast on a shaft 33 which is driven at the same speed as the main cam shaft of the match machine, the contour of the race being such that the bell-crank is oscillated thereby at determined 55 intervals to effect the timed reciprocation of the slide 25, as previously mentioned (see Figs. 1 and 2).

The slide 25 supports the expanded base 34 of a rearwardly extending arm 35 which is movable 60 in a path overhanging that of the carrier, the free end of this arm, at the limits of its forward and back movement, being somewhat beyond the respective sides of the carrier. Such end is provided with a cross structure 36 in the nature 65 of a T-head formed with spaced depending lugs 37 in and between which are pivoted two pendulous elements 38 of special construction, which elements are spaced apart correspondingly with the pockets of two adjacent links of the carrier. 70 Since the elements are alike in construction and operation, a description of one will suffice.

Each of the elements constitutes, in effect, a gravity dog having at its upper portion a hub 39 which is loosely mounted on a stud-shaft 40 fixed in and between a pair of lugs 37 of the

cross-member of the arm 35. Hence the axis of the dog is above and longitudinally of the carrier, which dog is of sufficient length to depend normally below the flanges of the adjacent link. The dog is formed with a laterally and forwardly extending base 41 adapted to overlie the flanges 21 of the adjacent carrier link while the dog is reciprocating from end to end of the link, as seen in dotted lines in Fig. 7. The forwardly projecting nose of the base is rounded, as at 42, and 10 the tail portion is downwardly and forwardly beveled or flared, as at 43. From the under side of the base 41 at the rear thereof, depends a bifurcated neck portion, the members 44 of which are movable freely through the space between the 15 link flanges. The neck members terminate respectively in laterally extending toes 45 arranged in spaced relation to each other and to the base 41 so as to underlie the respective flanges during the rearward stroke of the dog, as will 20 presently appear. The rear ends of the toes 45 present substantially vertical acting surfaces 46, and their forward ends are rounded or beveled, as at 47. The front faces of the neck members 44 curve downwardly and forwardly to the rounded or beveled ends 47 of the toes 45, as indicated at 48.

The center of gravity of each dog is such that when by actuation of the arm 35 the dog is moved outwardly beyond either side of the carrier and is in equilibrium the toes 45 lie below the plane of the under surfaces of the flanges, while the nose 42 of the base 41 lies partially below and above the plane of the upper surfaces of the flanges, as indicated in dotted lines at the 35 left of Fig. 6 and at the right of Fig. 8.

The body of the dog has an upward projection 48 which, when the dog is in its normal or vertical position during its rearward stroke, abuts a suitably-disposed rearward stop 49 when the toes 45 impinge the opposing match heads, thus limiting the forward swing of the dog. In the present instance this stop is constituted by a rod which is fixed to and between those lugs 37 of the supporting member 36 that embrace the hub 45 39 of the dog. A lower similarly supported rod 50 affords a stop with which the projection 48 abuts to limit excess upward movement of the dog during its initial forward stroke when the rounded nose 42 abuts the rear ends of the link 50 flanges 21.

The opening 51 between the spaced toes 45 of the depending dog enables the dog in its initial back stroke into the pocket of a link from which a cover has been omitted, to escape a block 52 55 which is fixed to the back wall of the trough 18 centrally of the entrance to the pocket so as to afford a support for the forwardly extending flap portion of a cover when present, as will be hereinafter described.

In Figs. 3, 4 and 5 of the drawings the slide 25 is represented at the limit of its forward stroke in respect to two adjacent links of the carrier, one link containing a cover and its complementary cards, and the other link containing match cards only. As seen, one of the dogs is in downwardly and rearwardly inclined position with the rounded forward portions 47 of its toes 45 resting upon the forwardly extending portion of the underlying cover C, thus supporting the rearward or acting portions of the toes above the proximate end of the link and the nose 42 of the base 41 slightly above the cover, while the other dog, being unsupported in the absence of a cover, has gravitated to its nor- 75

mal pendent position with its toes 45 forwardly of the cover-supporting block 52 and below the flanges of the link containing the match cards only.

5 In the initial back stroke of the slide 25 the inclined under surfaces of the toes of the supported dog immediately ride upon the opposing ends of the link flanges, thus camming the dog upward until the rounded trailing portions 47 10 of the toes rest upon the upper surfaces of the flanges, as seen in Fig. 7. As the stroke continues the dog rides freely upon the flanges until the toes 45 and the base 41 escape the link and the projecting folded end of the cover therein, 15 whereupon the dog gravitates to its normal position, as indicated in dotted lines at the left of Fig. 6.

Coincidentally with the described back stroke of the dog in relation to the link containing the 20 cover, the toes of the companion dog enter and traverse the pocket of the link containing the uncovered match cards, thus impinging the opposing heads of the matches beneath the flanges. At this instant the hanging portion of the latter 25 dog is moved slightly forward until the upper projection 48 thereof abuts the stop 49, whereupon the toes 45 impinge the match heads and forcibly push the cards rearwardly against the force of the underlying spring 22, thus ejecting 30 the match cards bodily from the carrier and beyond the rear side of the trough. This done the dog resumes its normal pendent position similarly to the companion dog, the noses 42 of the bases 41 of both dogs being slightly tilted down- 35 wardly in respect to the upper surface of the carrier (see dotted lines at left of Fig. 6).

In the initial forward movement of the slide 25 and the dogs 38 during each dwell of the carrier, the leading lower portions of the necks 44 40 where they merge with the ends 47 of the toes 45 of the respective dogs, abut the opposing folded end of the cover and the opposing base end of the uncovered match cards so that the toes 45 fulcrum on the opposing ends of the cover and cards until the noses 42 of the bases 41 of the dogs come in contact with the opposing upper portions of the respective link flanges 21 (as seen 45 at the left of Fig. 8), whereupon as the forward movement of the dogs continues the noses 50 of the bases 41 pivot against such portions and trail along the upper surfaces of the flanges. Hence the dogs are tilted with their respective toes 45 located above the links. As the dogs 55 approach the limit of the forward stroke the noses 42 of the bases 41 escape the underlying carrier links. The base of the dog which overhangs the cover sinks until the leading ends 47 of the toes 45 rest upon the flanges of the link, in 60 which case the base of the dog is maintained slightly above and out of contact with the cover, following which in the completion of the stroke, the toes 45 clear the end of the link and rest upon the cover, thus maintaining the dog in downwardly and rearwardly inclined position, with the base 41 above the surface of the cover and the rearward ends of the toes overhanging the ends 65 of the adjacent links, as seen in Figs. 4 and 6. Therefore in the succeeding back stroke of the 70 head the dog rides idly over the link which contains the cover, as previously described.

The lower end of the companion dog, being unsupported in the absence of a cover when it escapes the link, gravitates to its normal position preparatory to the succeeding back stroke

of the cover to eject the match cards, as hereinbefore mentioned.

If, perchance, an empty link should be positioned in the path of either of the dogs in its forward stroke, the forwardly projecting nose of the dog in its initial movement will directly come in contact with the opposing ends of the flanges of the link, and as the forward movement of the dog continues it will be tilted by and caused to trail along the upper surfaces of the flanges. At 10 the end of its forward stroke the dog will resume its normal position, and then in the succeeding back stroke the toes 45 of that dog will pass idly through the pocket of the adjacent link.

It is to be understood that my invention is not 15 limited to the particular exemplifying forms of embodiment thereof herein disclosed, as the mechanisms may be modified within the principle of the invention and the scope of the appended claims. 20

I claim:

1. In a match booking machine embodying a travelling carrier having pockets to receive and transport a succession of assembled covers and match cards, means for ejecting from the pockets cards from which the covers have been omitted, comprising a pendulous element extending normally below the path of the tops of the pockets and having an axis of oscillation above and longitudinally of said path, and means for 25 supporting said pendulous element and bodily reciprocating it in timed relation to the carrier in a path transversely of the carrier and beyond the respective ends of the adjacent pocket, said element including a base and a pusher spaced below and in co-operative relation to said base, whereby during the reciprocation of said element the base co-acts with and passes over the upper surface of the carrier, thus temporarily maintaining the element including the pusher 40 above and in inclined relation to the path of the carrier, and whereby said element when it passes beyond the forward end of a pocket from which a cover is absent descends to its normal position, thereby locating the pusher to enter 45 such pocket during the rearward stroke of said element, thus ejecting the opposing uncovered cards. 55

2. In a match booking machine embodying a travelling carrier having pockets to receive and 50 transport a succession of assembled covers and match cards, means for ejecting from the pockets cards from which the covers have been omitted, comprising a pendulous element extending normally below the path of the tops of the 55 pockets and having an axis of oscillation above and longitudinally of said path, and means for supporting said pendulous element and bodily reciprocating it in timed relation to the carrier in a path transversely of the carrier and beyond the 60 respective ends of the adjacent pocket, said element including a base and a pusher spaced below and in co-operative relation to said base, said base having a forwardly projecting nose portion and said pusher having a rearwardly projecting 65 portion, whereby during the reciprocation of said element the base co-acts with and passes over the upper surface of the carrier, thus temporarily maintaining the element including the pusher above and in inclined relation to the path of the 70 carrier, and whereby said element when it passes beyond the forward end of a pocket from which a cover is absent descends to its normal position, thereby locating the pusher to enter 75 such pocket during the rearward stroke of said 75

element, thus ejecting the opposing uncovered cards.

3. In a match booking machine embodying a travelling carrier having pockets to receive and transport a succession of assembled covers and match cards, each pocket having upper side flanges and a spring member co-acting with said flanges to provide a clamp for the covers and cards, and each of them, means for ejecting from 10 the pockets cards from which the covers have been omitted, comprising a pendulous element normally extending below the plane of the flanges, and means for supporting said pendulous element and bodily reciprocating it in timed 15 relation to the carrier in a path transversely of the carrier and beyond the respective ends of the adjacent pocket, said element having a base and a pusher connected by a neck portion and spaced below and in co-operative relation to the base, 20 said base and pusher being of greater width and said neck of less width than the space between

the flanges, whereby during the reciprocation of said element the base co-acts with and passes over the upper surface of said flanges, thus temporarily maintaining the element including the pusher above and in inclined relation to the path of the carrier, and whereby said element when it passes beyond the forward end of a pocket from which a cover is absent descends to its normal position, thereby locating the pusher to enter such pocket under the flanges during the 10 rearward stroke of said element, thus ejecting the opposing uncovered cards.

4. In means for removing from the travelling pocketed carrier of a match booking machine match cards from which covers have been 15 omitted, an ejecting element comprising a pendulous dog including a base having a nose portion, a neck depending from said base, and a match card pusher supported in spaced relation to the base by said neck.

JOHN R. NOLAN.
